LACE

Herman Kaufman, New York, N. Y.

Application December 24, 1948, Serial No. 150,348

Term of patent 14 years

(Cl. D47—6)

To all whom it may concern:

Be it known that I, Herman Kaufman, a citizen of the United States of America, residing in New York city, county of New York, and State of New York, have invented a new, original, and ornamental Design for a Lace, of which the following is a specification, reference being had to the accompanying drawing, forming part thereof, wherein, the figure is a plan view of a piece of lace showing my new design on a dark background so as to bring out more clearly the details thereof, a unit of which is contained within the dot and dash lines.

I claim:

The ornamental design for a lace, substantially as shown and described.

HERMAN KAUFMAN.
